US0D1091255S

(12) **United States Design Patent** (10) Patent No.: **US D1,091,255 S**
(45) Date of Patent: ** Sep. 2, 2025

(54) **FOOD PACK**

(71) Applicant: **WM. WRIGLEY JR. COMPANY**,
Chicago, IL (US)

(72) Inventors: **Yunjiu Gan**, Guangzhou (CN);
Changdan Li, Guangzhou (CN)

(73) Assignee: **Wm. Wrigley Jr. Company**, Chicago,
IL (US)

(**) Term: **15 Years**

(21) Appl. No.: **29/851,931**

(22) Filed: **Sep. 1, 2022**

(30) **Foreign Application Priority Data**

Mar. 1, 2022 (CN) 202230101503.3

(57) **CLAIM**

The ornamental design for food pack, substantially as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of the design of the present invention.

FIG. 2 is a rear view of the design thereof.

FIG. 3 is a left side view of the design thereof.

FIG. 4 is a right side view of the design thereof.

FIG. 5 is a top view of the design thereof.

FIG. 6 is a bottom view of the design thereof.

FIG. 7 is a perspective view of the design thereof.

FIG. 8 is a perspective view of the design thereof in an alternate configuration.

FIG. 9 is a perspective view of the design thereof in an alternate configuration in a use state; and,

FIG. 10 is a perspective view of the design thereof in an alternate configuration in a use state.

**1 Claim, 5 Drawing Sheets
